CLAIM

The ornamental design for an animal feeder, as shown and described.

DESCRIPTION

FIG. 1 is a top perspective view of an animal feeder in accordance with my new design;
FIG. 2 is a first side view thereof;
FIG. 3 is a second side view thereof;
FIG. 4 is a third side view thereof;
FIG. 5 is a fourth side view thereof;
FIG. 6 is a top plan view thereof; and,
FIG. 7 is a bottom view thereof.

1 Claim, 7 Drawing Sheets
